UNITED STATES PATENT OFFICE

GEORGE E. PANCOAST, OF SEA BRIGHT, NEW JERSEY

WEB PASTING MECHANISM

Original application filed January 22, 1924, Serial No. 687,757, now Patent No. 1,669,837, dated May 15, 1928.
 Divided and this application filed April 12, 1928. Serial No. 269,490.

This invention relates to certain improvements in web feeding and web joining or pasting mechanisms and is particularly adaptable for use in relation with a printing machine, and this application is a division of my co-pending application Serial No. 687,757, filed January 22, 1924, now Patent No. 1,669,837, dated May 15, 1928.

According to the present invention, there is provided a support for supporting a running web roll and a spare web roll with which is associated a web joining or pasting mechanism including a pair of rolls, one of which is movable toward and from the other, the parts being so positioned and arranged that a spare web may be led from a web roll in either the spare or running position and united with a web running from a roll in the other position to the press.

20 The invention has for its especial object an improved arrangement of the web rolls and the pasting rolls, so that a spare web having paste applied to its loose end may be simply dropped in either position between 25 the pasting rolls and there be united with the running web.

A further object of the invention is to provide roll driving devices by which the unwinding of the running roll may be controlled while the web therefrom is running to the press.

With these and other objects not specifically referred to in view, the invention consists in certain novel parts, arrangements and 35 combinations which will be described in connection with the accompanying drawings and the novel features pointed out in the claims hereunto annexed.

In these drawings,—

40 Figure 1 is a diagrammatic side view of the improved web pasting or joining mechanism and enough associated parts for an understanding of the advantages of the invention, and

45 Figure 2 is a side view on an enlarged scale of the pasting mechanism shown in Figure 1.

Referring now to these drawings, the invention has been illustrated as used with a 50 multi-couple printing machine employing

three active or running webs, in which machine the web pasting or joining mechanism and the roll supports are shown as located above the printing mechanisms, but it will be understood that the invention is intended 55 for use and may be used with other press arrangements. As shown, there is employed a three roll machine, the webs of which are indicated by the numerals 1, 2 and 3, these webs supplying printing couples which may 60 be arranged superposed in three decks, the upper deck only of which is illustrated. Each of these decks may include a pair of perfecting couples, each including form cylinders 4, 5, impression cylinders 6, 7 and ink- 65 ing mechanism, indicated generally by the numeral 8, for each form cylinder, these parts being supported in suitable framing 9. The webs from these couples are or may be slit and assembled over suitable guides 10 at a 70 longitudinal former 11.

In the construction illustrated there is provided for each printing and perfecting couple a running web roll and a spare web roll, the running rolls being indicated by the letter 75 R and the spare rolls by the letter S. These rolls are supported in suitable supports which may vary widely as to character, but in the particular construction shown the supports are so arranged that the web rolls are 80 loaded thereinto from above. As illustrated, these supports include frames 18 which are formed with bearing portions 16 for the roll spindles 17, these frames being supported in any suitable manner, not illustrated. The 85 rolls may be loaded into these supporting frames from a travelling carrier 25 provided with means for lowering a roll, such as a pulley 27, cable 28 and hooks 29, and this carrier may be conveniently moved along the framework 24 to the desired position above one of the roll bearings.

In accordance with the invention, means are provided to unite the end of a fresh web roll to an expiring roll without stopping the feeding movement of the webs, and a simple mechanism for effecting this, preferably in conjunction with a web controlling mechanism, is illustrated. In the particular construction shown, there is provided for each group, com- 100

prising a running web roll and a spare web roll, a pair of guide rolls 94, 95, and located below these guide rolls a pair of pasting or joining rolls. Each pair of these latter rolls includes what may be termed an abutment roll 96 over which the web runs, and this abutment roll may, if desired, be a driven roll, driven in any suitable manner, not shown. Cooperating with this abutment roll is a movable roll 97 carried in arms 98 on a rock shaft 99 suitably journalled in the frame of the machine, this rock shaft being manipulated through an operating handle 100, the roll 97 being thus capacitated to be moved to and from the abutment roll 96.

It will be observed that in the best constructions and as shown, the web rolls are arranged in horizontal alignment with the guide rolls above the pasting rolls. The end of a fresh web may have paste applied thereto and be hung over one of the guide rolls, as indicated at 107 at the two end positions in Figure 1 and the right end of Figure 2, or if desired the guide rolls 94, 95 need not be used, and the web simply dropped down from the web roll, as indicated in the center position in Figure 1 and at the left in Figure 2. When it is desired to effect a paste, the pasted end of the roll is dropped down between the abutment roll 96 and the roll 97, and the roll 97 is brought into contact with the abutment roll, thus squeezing the pasted new web against the expiring roll after the paste has been made. The expiring web may be separated or severed in any usual manner, as by breaking it with a stick.

In accordance with the invention, certain web controlling devices are used for driving the spare roll and for bringing the spare roll up to speed, and these devices will be such that they will be operated so as to operate on the spare roll at the time the paste is made, so that the paste may be made without stopping the press. While the construction of these driving and controlling devices may be somewhat varied, as illustrated, they include frictional feeding devices which are driven so as to effect the unwinding of the roll with the required nicety of tension.

In the particular construction illustrated, these feeding devices comprise a pair of belts 34, 35 arranged preferably, as shown, below the rolls, one set of these belts being used for each web roll. These belts are driven belts, being driven from gearing indicated at 76 from any suitable part of the press.

With the construction described it will be seen that a very simple arrangement has been provided for joining or pasting the end of a new web roll to an expiring web, and that this can be effected whether the web lead is from under or over the web roll. While the invention has been described in its preferred form, it will be understood that various changes may be made in the specific struc-

ture and arrangement shown and described without departing from the invention as defined in the appended claims.

What I claim is:

1. In a web feeding and pasting mechanism, the combination of a support for a running web roll and a spare web roll, a pair of pasting rolls below the web rolls arranged horizontally, between which a spare web may be led directly either over or under from a web roll in either position, guides over which the end of a spare web may be suspended and located above the pasting rolls, and means for moving one only of the pasting rolls toward the other to join the new web to a web running to the press. 70

2. In a web feeding and pasting mechanism, the combination of means for supporting a running web roll and a spare web roll in side by side relation, a pair of pasting rolls located below the web rolls and arranged so that spare web may be led from a web roll in either position, guide rolls located above the pasting rolls and over which the end of the spare web may be suspended 35 in pasting position, and a single means for bringing the pasting rolls into pasting relation to join the new web running from either position to a web running to the press. 50

In testimony whereof, I have hereunto set my hand.

GEORGE E. PANCOAST.
